PROPANE OPERATED HEATER FOR WATER COOLED ENGINES OR THE LIKE

Seth B. Lindsey and John H. Klancke, Minneapolis, Minn., assignors to Phillips Manufacturing Company, Inc., Minneapolis, Minn., a corporation of Minnesota

Filed Apr. 22, 1966, Ser. No. 1,982

Term of patent 14 years

(Cl. D81—1)

FIG 1

FIG 2

FIG 3

FIG 4

FIG 5

FIG. 1 is a front elevational view of a propane operated heater for water cooled engines or the like embodying our new design;

FIG. 2 is a side elevational view thereof;

FIG. 3 is an opposite side elevational view thereof;

FIG. 4 is a top plan view thereof; and

FIG. 5 is a bottom plan view thereof.

A rear elevational view is substantially a mirror image of FIG. 1.

We claim:

The ornamental design for a propane operated heater for water cooled engines or the like, as shown and described.
